AUTOMATIC CASINGHEAD EQUIPMENT

Frederic W. Hild, Los Angeles, Calif.

Application July 28, 1930, Serial No. 471,114

15 Claims. (Cl. 166—15)

My invention relates to the control and prevention of fluid blow outs from wells.

It is an object of my present invention to provide equipment which shall automatically function to prevent escape of the well fluid upon the earliest manifestation of unstable fluid conditions in the well casing.

Another object of my invention is to provide an automatic casing valve which shall close automatically upon withdrawal of the drill from the casing.

Another object of my invention is to provide a blow out prevented in the casing valve for co-operation with the drill string.

Another object is to provide an automatic mud valve which shall automatically close the well outlets upon change of specific gravity of the fluid passing through the valve and/or upon change of the fluid level and/or upon change of the rate of the fluid flow.

Another object is to provide for concentrically disposed well casings—terminal collars having vent heads and vent pipes at substantially the same common level.

Certain other features of my present invention are improvements of those disclosed in my co-pending applications Serial No. 382,384, filed July 31, 1929, now Patent No. 1,938,020 and Serial No. 385,270, filed August 12, 1929, now Patent No. 1,906,265.

Other objects and advantages of my invention will be apparent from the following descriptions and the accompanying drawings:

Figure 1 is a vertical elevation of the apparatus embodying my invention.

Figure 2 is a vertical section of Figure 1.

Figure 3 is a vertical section of the automatic mud valve.

Figure 4 is a vertical section taken on the line 4—4 of Figure 3.

Figure 5 is an end view of the mud valve outlet.

Figure 6 is a horizontal part section taken on the line 6—6 of Figure 2.

Figure 7 shows in vertical section another view of the automatic casing valve showing the valve gate in intermediate and closed positions.

Figure 8 is a horizontal plan view in part section taken on the line 8—8 of Figure 2.

Figure 9 is a horizontal view in part section of the casing valve.

Figure 10 is a vertical elevation in part section of the casing valve.

Figure 11 is a view in part vertical section showing the springs and pistons for closing the gate of the casing valve.

Figure 12 is a diagrammatic view of the moving parts of the casing valve.

Referring to the drawings, the casings 15, 16, 17 and 18 are threaded into and suspended from casing terminal collars 19, 20, 21 and 22 respectively which in turn rest upon foundation 23. The automatic casing valve 25 is secured to the casing terminal collars by flange collar 24. The main or axial outlet of the casing valve contains the axial blowout preventer 26 through which the kelly or drill stem 27 extends; a split socket wrench 28 is engaged by the rotary machine 29 for tightening or freeing the preventer 26 in the casing valve 25. The automatic mud valve 30 is connected by the pipe 31 to a lateral outlet 15 of the casing valve 25.

Terminal collar 19 is seated in and contained by terminal collar 20; likewise collar 20 is seated in terminal collar 21 which in turn is seated in and contained by terminal collar 22. Packings 31 supplement the tight fits between the terminal collars in providing fluid tight joints between the casings. In order to control fluid which might accumulate between the strings of casings, channels leading to suitable vent heads are formed in 25 the outer terminal collars, none being needed for the innermost collar when it is for the final, or oil string. Thus channels 32 extend to vent heads 33 of terminal collar 29, and into the vent heads are threaded the usual vent pipes 34 which 30 have hand operated valves (not shown). In like manner terminal collar 21 has channels 35, vent heads 36 and vent pipes 37. Outermost terminal collar 22 has channels 38, vent heads 39 and vent pipes 40.

Flange collar 24 is threaded fluid tight into the innermost terminal collar 19 and is also secured by bolts 41 to the outermost casing terminal collar 22, thereby adding the force exerted by the bolts to the force due to the heavy weight 40 of the suspended casings in firmly seating each terminal collar in the adjacent containing collar so as to lock them all together solidly as a unit. The flange collar 24 has the thread 42 for receiving the "Christmas Tree" pipe assembly for flowing well or a tubing head for pumping. Obviously when the innermost string of casing is the oil string and therefore the final string, the flange collar and the oil string terminal collar can be one piece instead of two.

The casing valve 25 is secured fluid tight to the flange collar 24 in any suitable manner as by tongues and grooves 44 and bolts 43. The casing valve body 45 has a lateral outlet 46 to which the automatic mud valve 30 is connected and 55

another lateral outlet 47 which is kept normally closed by a hand valve (not shown). This outlet 47 is used to admit mud fluid or to draw off well fluid under certain conditions of drilling or bringing in the well. Into the main or axial outlet of the casing valve body 45 is firmly secured the valve bushing 48 the under face of which forms the valve seat 49 and against which the valve gate 50 automatically swings to close the axial outlet when the valve body does not contain pipe or the drill string. The valve gate 50, circular in form, has a central pin 51 which is engaged by the trunnion arm 52. The central pin 51 may rotate loosely in the trunnion arm 52 so as to permit the valve gate 50 to adjust itself into good closing contact with valve seat 49. For convenience of assembly the trunnion arm 52 is in two parts bolted together and is pivoted in the valve body 45 by the trunnion pins 53 which are held in place by the blind plugs 54. The trunnion arm 52 has crank pins 55 against which force may be exerted to swing the trunnion arm upwardly or downwardly and thereby close or open the casing valve 25.

Upward movement is by one or both of two forces, one force being that of a pair of springs which always act to automatically close the casing valve. The other force is by any suitable pressure such as by the mud pump, or steam, or the water supply system of adequate pressure. Two cylindrical holes 56 bored in the valve body 45 contain the hollow pistons 57. Within each piston is sleeve 58 containing the helical spring 59 which resting on the inner bottom of the piston, acts always to force the sleeve 58 upwardly against crank pin 55. The cylinders 56 at their lower ends communicate with fluid channel 60 which in turn communicates with inlet 61. This inlet is controlled by a suitable triple valve 62 which connects with the mud pump or other fluid pressure supply. The triple valve also controls the discharge opening 63 which permits fluid to drain from the cylinders 56 and from fluid channel 60 into the well casing. A "two-way" valve, the same as triple valve 62 has been described and illustrated in detail in my co-pending application Serial No. 384,213 for Automatic blowout preventer, filed August 7, 1929. Rotating the triple valve 62 in one direction admits fluid under pressure to cylinders 56 and forces the pistons 57 upward against crank pins 55, this force being additional to the force of the springs 59 for closing the valve gate 50. Movement of the triple valve 62 in the opposite direction shuts off the fluid supply and opens discharge opening 63 draining the fluid from the cylinders 56 into the well casing whereupon the pistons 57 will move down to their bottom positions.

The cylinders are closed at the top by blind plugs 64 through one of which the casing valve stem 65 is threaded. The valve stem 65 may be rotated downward against a crank pin 55 to force and hold open valve gate 50. Reverse rotation of the stem backs it against its seat in blind plug 64 thus effectively preventing leakage past the threads of stem 65. A second means for holding open the valve gate is provided by the ring 66 which rests upon a ledge 67 in the valve body 45. The inner bore of the ring is less than the diameter of the drill bit 68 but sufficiently large to freely pass the tool joints or couplings and the protectors. Just before threading the bit into the drill collar of the drill string, the ring 66 is placed on the drill collar above the

bit, and when the bit is lowered through the valve 25, the ring encounters the ledge 67. The valve stem 65 is then backed off permitting the springs 59 to force the valve gate 50 against the ring 66. On "coming out the hole" the ascending bit 68 intercepts the ring 66 and carries it upward, whereupon the springs 59 automatically close the valve gate 50 against its seat 49. Should there also be upward movement of the well fluid, this too will act to force the valve gate 50 upward into its seat, and the well fluid pressure will be added to that of the springs in maintaining closure of the casing valve 25.

The valve bushing 48 has external thread 69 for receiving locking nut 70. The upper end 15 of the locking nut forms the outer half of breech lock 71. An upwardly extending lug 72 of the valve body 45 has an adjustable set screw 73 for limiting unscrewing of the locking nut 70 from valve bushing 48. A ring 74 projecting from the 20 locking nut 70 intercepts the set screw 73 for this purpose.

The axial blowout preventer 26 may be assembled on the kelly 21 and lowered therewith into bushing 48 of casing valve 25 and may rest upon ring 66. A tapered plug 75 has a central opening for snug sliding fit on the drill stem, and has outwardly the form of a truncated cone. The plug consists of packing 76 which may be of rubber moulded on to two metal pieces, one the plug 30 top 77 and the other the plug bottom 78. The plug is journaled in the taper bored preventer shell 79 the outer lower part of which is threaded to receive the retaining ring 80 and also the jam ring 81 for locking the retaining ring in position. 35 The retaining ring has an annular projection which limits the downward movement of the plug 75 and upon which the plug may rotate. Upward movement of the plug is restricted by the taper bore of the preventer shell 79. When the 40 plug is moved upward as by lifting the drill stem 27 or by pressure of the well fluid, the rubber packing 76 is forced against the taper bore which causes compression of the rubber inwardly so that it packs more tightly against the drill stem. 45 When extremes of pressure are encountered, the plug top 77 and the plug bottom 78 which are made of metal, are also forced against the taper bore of shell 79. The upper portion 82 of shell 79 is a hollow cylinder in form and has an outwardly projecting shoulder 83. An inward ledge 84 on the bushing 48 intercepts shoulder 83, so that if ring 66 be omitted, downward movement of the blowout preventer 26 is nevertheless limited and it cannot fall through into the well. An 55 annular packing ring 85 of rubber or like material is formed on the portion 82 and rests upon the shoulder 83. Resting upon and in position to press down upon the packing ring 85 is locking member 86 which at its upper outer portion 60 constitutes the inner mate to the breech lock 71 of the locking nut 70. The upper inner portion of the locking member 86 is hexagonal in form to receive the hexagonal socket wrench 28.

The socket wrench 28 is of two parts hinged 65 together so that the wrench may be placed around the kelly and lowered into the hexagonal socket of locking member 86. Upon rotating this socket wrench as by the rotary machine 29, the locking member 86 will first be rotated into locking engagement with breech lock 71 and continued rotation will screw the locking nut 70 downward carrying with it the locking member 86. This will exert downward pressure on the packing ring 85 forcing it tightly against shoulder 83 of shell 75

79 and against the walls of valve bushing 48 and cylindrical portion 82 of the shell 79 thus effectively preventing the escape of the fluid past the outside of the preventer 26 and firmly locking the 5 preventer into the casing valve 25.

The automatic mud valve 30 has the body 87 containing two compartments one for the specific gravity valve 88 and the other for the flow level valve 89. A cover plate 90 encloses the two 10 compartments except for valve inlet 91 and valve outlet 92. Between the two compartments is opening 93 which is the outlet for the specific gravity valve 88 and the inlet for flow level valve 89. The specific gravity gate 94 is of wood or 15 other material which will float in ordinary mud fluid but which will sink when the specific gravity of the mud fluid is diminished as by water dilution or gas. The valve gate 94 swings on pin 95, the ends of which are secured in blind holes in 20 the body 87 and the cover plate 90.

The flow level valve gate 96 is outside hung by reason of its lever arm 97 which swings on pin 98, the pin being secured to body 87 outside and 25 above the valve outlet 92. The valve gate 96 has limited movement about pin 99 of the lever arm 97 so that the valve gate may be self-adjusting when against its valve seat at outlet 92. Hung on the same pin 98 is pilot gate 100 which normally closes outlet 92 when no liquid flows through 30 it. When however liquid begins to flow through the valve and from outlet 92, the pilot gate 100 swings outwardly and actuates a signal such as an electric buzzer to indicate flow and conversely cessation of flow. As the flow level in the valve 35 rises the flow ultimately encounters the valve gate 96 and acts to swing the gate to close the valve. A counter balance arm 101 serves to diminish the required pressure for swinging the valve gate. Both the valve lever arm 97 and the 40 pilot gate 100 are provided with jaws on their adjacent faces at the pin 98; these jaws intercept when the pilot gate swings out to a sufficient angle with respect to the lever arm 97 so that the pilot gate assists the valve gate 96 in effecting closure 45 of the automatic mud valve.

A pipe 102 controlled by hand valve 103 is threaded into the top of specific gravity valve compartment 88. Likewise a pipe 104 controlled by hand valve 105 is threaded into the top of flow 50 level valve compartment 89. The two pipes are for several purposes: Thus pipe 102 may serve as an air vent when mud fluid rises in specific gravity valve compartment 88; or it may be used to draw fluid from the well casing; or it may admit 55 mud fluid or the like to close the specific gravity valve gate 94 and to replenish the mud supply in the casing. Pipe 104 may admit mud fluid to close the flow level valve gate 96 and to open valve gate 94, and also to replenish the mud 60 supply in the well.

When the casing valve 25 has been closed whether by the hydraulic pistons 57, the springs 59 or by the well fluid pressure,—it may be required to hold the valve gate 50 firmly closed and relieve the pistons and the springs of this duty. Such a means is shown in Figure 7; a threaded hole in the center of valve gate 50 receives the threaded end of stem or handle 106 to 65 which is secured circular plate 107 which fits into valve bushing 48 and is forced by the handle 106 tightly onto a shoulder 108 of said bushing.

Considering the operation of the apparatus it should be noted that the outlet 92 of the automatic mud valve 30 is at a higher level than the 70

top of taper plug 75, so that the plug rotates in the mud fluid which serves as its lubrication.

When the mud fluid ceases to flow from outlet 92, whether because of automatic closure of either of the two valve gates in the mud valve 30, or because of interruption or "loss" of the mud circulation,—the pilot gate 100 will at once indicate the cessation of flow and conversely also the resumption of flow. 5

When the drill releases high underground pressures, this usually results in diluting the mud fluid by gas. The specific gravity valve gate 94 will then sink and automatically close the outlet, whereupon the well fluid will seek escape at the axial outlet of casing valve 25 which contains the blowout preventer 26 and the kelly 27. The rising fluid will carry the preventer plug 75 firmly into its tapered seat in shell 79. Should the circulating mud be "lost" as in large cavities or by infiltration or should the mud level be 20 otherwise lowered as when withdrawing the drill string, the valve gate 94 will descend to closing position. 10

Under certain other conditions of well drilling and in certain oil fields, the bit may release high 25 underground pressures which may result in unstable equilibrium of the mud column in the well without sufficient change of its specific gravity to permit the valve gate 94 to sink. In such event upon rise of the fluid flow through outlet 30 92 of the mud valve 30, the flow level valve gate 96 will automatically close the mud valve outlet with consequent automatic closure of the axial outlet of casing valve 25 by the blow out preventer 35 plug 75.

In this embodiment of my invention, the bushing 48 serves as the valve seat and other casing valve purposes. However considering the bushing 48 and the several parts secured and contained by it, it is manifest that the bushing 48 may be secured into any other kind of casinghead. The rapid, simple operation of inserting and locking the preventer 26 into bushing 48 of casing valve 25 or other equivalent casinghead, and its equally facile removal therefrom, all from the derrick 40 floor,—made possible by my invention—eliminates a dangerous hazard to the workers who for other types of preventer devices have been required to do this work at the casinghead under the derrick 45 floor. 50

Upon withdrawing the kelly, a split packer for round drill pipe similar to that illustrated in my aforesaid co-pending application Serial No. 385,-270 may be inserted in bushing 48 of the casing valve or equivalent casinghead and quickly locked 55 in place by the means provided by my invention.

In the event of unstable fluid conditions as the drill is finally withdrawn, it is manifest from the previous description that both the casing valve 25 and the mud valve 30 will close automatically 60 thereby anticipating and effectively preventing blowout from the well casing.

Fluid pressure within the casing valve is exerted upon the flange collar 24 and the innermost terminal collar with resultant increase of pressure and tighter seating of each inner terminal collar into its adjacent containing terminal collar, thereby more effectively preventing blowout between the casings. 65

The terminal collars provided by my invention 70 possess other important advantages and benefits. By combining the flange collar 24 with the final innermost terminal collar, the irreducible minimum number of parts for suspending and anchoring the casings in interlocking support, namely 75

one part for each string of casing, and the minimum number of possible leakage paths are achieved.

Terminal collars which with their vent heads 5 and vent pipes are disposed at a common level instead of being superimposed, make possible the termination of the casings at about the ground level thereby eliminating the "cellar", and enables installing the casinghead equipment in the relatively small space between the ground surface and the derrick floor,—all of which are important contributions to safety for the men and the entire installation, and to greater facility of operation, inspection and maintenance.

15 Although I have described several specific embodiments of my invention, it will be obvious to those skilled in the art, that various modifications may be made in the details of construction, the general arrangement, the association of the several co-operating parts and the application of my invention without departing from the spirit thereof or the principles herein set forth.

I claim as my invention:

1. A blowout preventer for automatically preventing the blowout of a fluid from a casing head, comprising a valve mechanism having a plurality of pivoted valve gates each independently controlling the flow of fluid therethrough, manually operated means for opening and closing one of said gates, and manually controlled means for admitting fluid under pressure into the valve mechanism between gates for opening one gate to permit said fluid to pass into the well, and for closing the other gate to prevent fluid from escaping from said head.

2. A valve for controlling fluid flow from a well, and a valve gate normally floating in said fluid, passing through said valve and sinkable therein upon decrease of the specific gravity of said fluid.

40 3. In apparatus for preventing blowout of fluids from a well casing head, means forming an outlet from said head, and a valve closure mechanism for the outlet, said closure mechanism being so constructed and arranged that it is actuated to close the outlet by any of the following: a decrease in specific gravity of the fluid; an increase in the pressure thereof; a rise of fluid level in the casing.

4. In apparatus for preventing blowout of fluids 50 from a well casing head, means forming an outlet for fluid from said head, and a valve closure for the outlet, so constructed and arranged that it is actuated to close the outlet by a rise of fluid level in the casing.

55 5. In apparatus for preventing blowout of fluids from a well casing head, means forming an outlet chamber from said head, said chamber being below the level of fluid at normal operation, and a submerged movable closure in the chamber 60 for the outlet and having a definite specific gravity so that its position in the chamber is dependent upon the specific gravity of the fluid.

6. In apparatus for preventing blowout of fluids 65 from a well casing head, means forming an outlet chamber from said head, said chamber being below the level of fluid at normal operation, means forming a closure for the outlet, and submerged in the chamber, and a pivotal support for the means, said means having a definite specific 70 gravity so that its submerged angular position on its pivot depends upon the specific gravity of the fluid.

7. In apparatus for preventing blowout of fluids from a well casing head, means forming an outlet chamber from said head, said chamber be-

ing below the level of fluid at normal operation, and a submerged closure in the chamber, said closure being pivoted above a seat in the chamber and extending from the pivot toward the inlet side of the chamber, said closure having a definite specific gravity so that its angular position in the chamber becomes nearer vertical upon a decrease in specific gravity of the fluid, and in position to be acted upon by the fluid pressure to effect complete closure of the outlet.

8. In apparatus for preventing blow-out of fluids from a well casing head, means forming an outlet conduit from said head, said conduit having an opening substantially at normal fluid level, and a movable valve closure for said opening, said closure being in the path of flow of fluid when the fluid level rises above a definite level higher than the lower limit of the opening, whereby said closure is moved by said fluid to close the opening.

15 9. A blow-out preventer for a casing head, comprising means forming a fluid outlet from the casing head, a pair of separated valve closures for closing the outlet, means for so supporting said closures that fluid pressure in the casing may maintain said closures in closed position, and means intermediate said closures for conducting fluid under pressure into the head past one closure while causing the other closure to close.

20 10. A blow-out preventer for a casing head, comprising means forming an upwardly directed fluid outlet from said casing head, a pair of valve closures in said outlet, one of said closures being in the lower end of the outlet, and the other being in the higher end thereof, means for supporting the lower closure so that it may be maintained in closed position by pressure inside the casing, means for supporting the upper closure to be in the path of fluid escaping from the outlet when the fluid level exceeds a definite point, and means for admitting fluid under pressure between said closures, to open the lower closure for the entry of said fluid, and to close the upper closure.

25 11. In apparatus for preventing blowout of fluids from a well casing head, means forming an outlet from the head, said means providing a pair of valve seats on opposite sides of the end of the outlet, a pair of closures coacting respectively with said seats, and means forming a common pivot above the seats, for both closures.

30 12. In apparatus for preventing blowout of fluids from a well casing head, means forming an outlet from the head, said means providing a pair of valve seats on opposite sides of the end of the outlet, a pair of closures coacting respectively with said seats, means forming a common pivot above the seats, for both closures, and means whereby opening movement of the outer closure assists the closing movement of the inner closure.

35 13. In apparatus for preventing the blowout of fluid from a casing head, having an outlet, a valve mechanism in the outlet for controlling it, said valve mechanism including means for closing the outlet, actuated by a reduction in the specific gravity of said fluid below a desired minimum value, or by an increase in pressure thereof, above a desired maximum value.

40 14. In apparatus for preventing blow-out of fluids from a well casing head, means forming a fluid outlet from said head, and a valve mechanism for controlling said outlet, said mechanism including a member actuated in response to variations in specific gravity of the fluid and moved to

cause the valve mechanism to close upon a reduction in the specific gravity below a desired minimum value.

15. In apparatus for preventing blow-out of fluids from a well casing head, means forming an outlet from said head, and a valve closure mechanism for controlling said outlet, said valve

closure mechanism including a member normally floating in fluid passing through the valve mechanism and acting in response to a reduction in the specific gravity of the fluid below a desired value, to cause the outlet to close.

5

FREDERIC W. HILD.
